HIS ATTORNEY.

UNITED STATES PATENT OFFICE

JOHN K. NORTHRUP, OF BURBANK, CALIFORNIA

AUTOMATIC FLUSHING VALVE

Application filed January 12, 1929. Serial No. 331,982.

My invention relates to flushing valves, and particularly to automatic valves for flushing sewerage systems at stated intervals.

An object of my invention is to provide an automatic flushing valve which does not require special manhole construction, and is interchangeable with manually operated valves.

Another object of my invention is to provide a valve seat which is automatically cleaned, thus ensuring positive action of the valve and preventing waste of water.

Still another object of my invention is to provide an automatic valve in which the working parts are not exposed to the highly corrosive action of sewer gases.

Further objects of my invention are to provide a valve having few and simple working parts, which is easy to install, and one which is adjustable thru a wide range of operating conditions.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

The drawing is a side elevation of a valve embodying my invention, installed in a flushing manhole of the usual type. The manhole is shown in section.

Considered broadly, my invention comprises a valve gate having suitable operating means attached thereto. A float is movably mounted with respect to the operating means, and is arranged to engage this means at its limits of motion to actuate the valve. In this manner the opening and closing of the valve are accomplished suddenly, and the motion of the gate itself has no bearing on the motion permitted the float, and hence on the head of water available for flushing. Furthermore, as will be shown, this arrangement permits the valve seat to be placed vertically, which tends to keep it clear of obstruction, and also permits the valve to be closed while still under water, which not

only contributes to the same result, but also prevents the escape of sewer gases.

In the embodiment of my invention shown in the drawing, the valve is installed in a manhole 6 of the usual type, thru the side 55 of which, adjacent the bottom, passes the sewer pipe 7. Over the end of the pipe the ring 8 is cemented, which has the valve seat 9 formed on its face.

The valve itself is of the type disclosed in 60 my copending application, Serial No. 255,617, filed February 20, 1928, and comprises a gate 11, loosely hinged on a pin 12 to hang in front of the seat. The gate has a gasket 13 on its face to ensure tight contact with the 65 seat, and from its back projects an arm 14 to which an operating lever 16 is pivotally mounted. The arm 14 is preferably doubled or forked to receive the end of the lever, with a web 17 between the two halves. 70

Secured to the ring 8 adjacent the valve seat are a pair of bars 18 whose ends are bent inwardly to provide inclined fulcra 19. The lever 16 is bent, and its shorter and approximately vertical arm carries a pin 21 which 75 engages the fulcra when the lever is pressed downward, so that the gate is pressed inward against the seat and also partially lifted from the pin 12.

As thus far described, the valve is identical 80 with that of my previous disclosure. The lever 16, however, differs from that there shown in having a stop 22 which engages the web 17 to limit its motion with respect to the gate, and also in having a divided outer 85 end between the forks of which a fitting 23 is pivoted on the pin 24. The fitting serves to attach to the lever a rod 26 which extends upward to a point adjacent the top of the manhole, or to a distance governed by the 90 quantity of water it is desired to store, in case the manhole is over 8 feet deep.

Set in the masonry of the manhole and held by means of a tang 27 is a horizontal forked bracket 28, near the outer end of which is pivoted a toggle lever 29. This lever is also forked, and a bronze tension spring 30 between the forks of the bracket and lever connects the two to give them the familiar 95 spring-toggle action. The pivoted end of 100

the lever is carried out in arcuate form with or pivot pins. The other parts may be of the pivot at the center, and an adjustable U-shaped stop 31 is mounted on the arcuate portion to limit the throw of the lever. The stop is secured to the lever by a set screw 32. The force required to carry the toggle past center varies with the throw, and by setting the stops, the action of the valve may be regulated.

10 The rod 26 is connected with the toggle lever by a fitting 33 which is similar to the fitting 23 connecting it with the valve lever. Mounted on the rod is a float 34 which has a tube 36 passing through its center. The tube is of such size as to slide easily on the rod. 15 An adjustable stop 37 is also mounted on the rod to limit the motion of the float thereupon.

In use, a constant small stream of water is allowed to flow into the manhole, gradually filling it, and raising the float on the rod. 20 This continues until the float strikes the stop 37, as shown in the drawing, after which the water level continues to rise on the float until its buoyancy is sufficient to overcome the force of the spring 30, raising the toggle 25 lever and with it the rod and the operating lever of the valve. Since the mechanical advantages of the spring decrease rapidly with motion, and the float is deeply submerged and therefore stores considerable energy before it 30 can overcome the force of the spring, the instant the toggle lever starts to lift it carries past center and opens the valve wide. As the water in the manhole escapes, the spring 35 keeps the valve open while the float slides down the rod until it strikes the lever 16, where it rests until its weight, unsupported by the water, is sufficient again to throw the toggle and close the valve.

40 The amount of water remaining in the manhole when the valve closes may be adjusted by the stop 31, regulating the throw of the toggle lever. The water level at which flushing takes place may be regulated in a similar manner, and also by adjusting the stop 37. A similar stop may, of course, be mounted on the rod below the float to connect the two operatively before the float sinks to the level of the lever 16.

50 An important feature of the device is that it is fully interchangeable with the manually operated valve described in my previous application, requiring only the substitution of the lever 16 in so far as the valve itself is concerned. Changing requirements in a sewerage system frequently make changes from automatic to manual operation or the reverse desirable, and with this apparatus such changes may be made with a minimum of trouble and expense.

60 It is understood that the parts of the valve should preferably be resistant to corrosion. Not only the spring for holding the valve open and closed should be made of bronze or similar material, but also the various hinge

or pivot pins. The other parts may be of iron or steel galvanized or otherwise treated to prevent rust.

I claim:

1. An automatic flushing valve comprising 70 a valve seat, a movably mounted gate engageable with said seat, a fulcrum adjacent the seat, a lever mounted on the gate and engageable with the fulcrum to press the gate against the seat, a rod connected to the lever, a float slidably mounted on said rod, and means for limiting the movement of the float upon the rod to connect operatively the rod and float. 75

2. An automatic flushing valve comprising 80 a valve seat, a movably mounted gate engageable with said seat, a fulcrum adjacent the seat, a lever movably mounted on the gate and engageable with the fulcrum to press the gate against the seat, means for limiting the movement of the lever with respect to the gate, a rod connected to the lever, a float slidably mounted on said rod, and means for limiting the movement of the float upon the rod to connect operatively the rod and float. 85 90

3. An automatic flushing valve comprising a valve gate, a spring actuated toggle operatively connected to said gate, a float arranged to throw said toggle to operate the valve, and an adjustable stop arranged to 95 limit the movement of the toggle.

4. A valve comprising a gate, a spring connected to open and close the gate, and a float arranged to initiate the action of the spring, and means for adjusting the float pressure required to initiate said action. 100

5. An automatic flushing valve comprising a valve gate, means for suddenly opening said gate, a float for operating said opening means, and means for adjusting the force on said float required to operate said gate. 105

6. An automatic flushing valve comprising a valve seat, a movably mounted gate engageable with said seat, a fulcrum adjacent the seat, a lever mounted on the gate and engageable with the fulcrum to press the gate against the seat, means for limiting the movement of the lever with respect to the gate, and control means for actuating the lever to operate the gate. 110 115

In testimony whereof, I have hereunto set my hand.

JOHN K. NORTHROP.
